UNITED STATES PATENT OFFICE.

MAXWELL M. UPSON, OF NEW YORK, N. Y.

WHARF OR PIER.

Application filed June 13, 1923. Serial No. 645,060.

This invention relates to wharf or pier constructions, and while it is useful in a large variety of situations it is designed (in the form herein illustrated) for use in rivers, 5 deltas, estuaries, bays, and the like, where the underlying bed is composed of soft material to great depths, or where there is an extreme variation between high and low water or where both these conditions are 10 found. For example, it is well known that in the Mississippi River the difference between "high" and "low water" is very great. Moreover the soil composing the bed of the Mississippi (at least in the lower reaches of 15 the river) is soft to a considerable depth, and hence affords no secure anchorage to piles. The result is that great difficulty has been experienced in building in parts of that river, wharves which will stand for an 20 extended period of time the severe stresses to which they are subjected, as by the impact of steamboats in making a landing, the swift current at times incident to "high water", the outflow of accumulated silt as the high 25 water recedes, and other harmful influences. I have therefore been led to devise my present invention which has for its object to provide a wharf or pier construction which can be erected at reasonable cost and which 30 will withstand indefinitely the destructive agencies encountered in such locations as the lower reaches of the Mississippi, where, for example, the bed soil is soft to a depth of a hundred feet or more and where the vertical 35 difference between low and high water is upwards of fifty feet. To this and other ends the invention which I desire to cover by Letters Patent embraces all the novel features hereinafter described.

In carrying out the invention in the preferred manner, concrete piles are driven 40 into the river bed in a plurality of transverse groups or series, forming bays, the piles being as long as possible and sunk far enough 45 to bring their upper ends to a point about, say, half way between average high and average low water. Thus if the difference 50 between high and low water is fifty feet the piles would stand twenty or twenty-five feet above low water. Some of the 55 piles in each group may be given a transverse batter or slant, to aid in resisting bending stresses such as would be caused by a steamboat or other vessel ramming the wharf. On top of the piles, and integral therewith, is a framed structure of concrete

having a deck (which may be of wood) and extending high enough above the piling bays to bring the deck above high water. This superstructure is composed of bays, all parts 60 of which are integrally connected, and its elements are spaced widely, as are the piles also, so as to cause the minimum obstruction to the river current consistent with the desired rigidity and strength of the wharf, the 65 main portion of which, it will be understood, must in some if not most cases stand out in the river a considerable distance from low water mark on the sloping bank or levee. One or more approaches, preferably of the 70 same construction as the main portion of the wharf, connect the same to the bank for the passage of trucks and teams, and I may also provide one or more transverse piers or stiffening structures extending to or toward 75 the bank. These stiffeners also provide convenient storage space and may have sheds for the purpose, if desired.

A construction such as is briefly described above is illustrated in the accompanying 80 drawings, in which

Fig. 1 is a perspective view showing a long wharf set well out from the bank, with an approach at each end, and provided with two stiffeners between the approaches. In 85 this figure the water in the river is shown at a high stage.

Fig. 2 is a detail cross section about on line 2-2 of Fig. 1. In this figure a low stage of water is indicated by the line 1-1.

Fig. 3 is a detail perspective view of a portion of the decked superstructure.

Fig. 4 is a detail side view, from the right of Fig. 2, of a portion of the superstructure.

Fig. 5 is a detail sectional plan view of 95 one of the footings of the wharf, taken about on line 5-5 of Fig. 2.

Fig. 6 is a detail cross section of one of the stiffeners, about on line 6-6 of Fig. 1.

Fig. 7 is a detail side elevation of a portion of the stiffener.

Fig. 8 is a detail sectional plan view of a footing of the stiffener, about on line 8-8 of Fig. 6.

The wharf or pier illustrated in Fig. 1 105 comprises a main portion 10 set out from the river bank 11 and more or less parallel thereto. Two approaches, 12, 13, are shown, one at each end, and two stiffeners 14, 15, the first of the latter extending to the bank 11. The substructure of the main portion 110 of the wharf is composed of long substan-

tially vertical concrete piles 16, Figs. 2, 3, 4 and 5, arranged in transverse rows or groups which are spaced apart longitudinally to form bays. At the outer end of each group 5 or row are two batter piles 17 extending inwardly (toward the bank) and at the other end two batter piles 18, 19, the former extending inwardly and the latter outwardly. The approach piling is also of concrete and 10 may be and preferably is similarly arranged, as may also be the piling of the stiffeners, but in the latter the arrangement is preferably as indicated in Figs. 6, 7 and 8. As there shown, four piles are used in each 15 group, an upright pile 20 at each end of the group and two intermediate batter piles 21, 22, extending inwardly and outwardly.

The concrete superstructure of the main portion and approaches comprises transverse 20 sills or caps 23, Figs. 2, 3, 4 and 5, one on each row of piles and integral therewith, the reinforcing members of the piles projecting into the sills, as indicated in Fig. 2, to bond the parts together. At each end the sills are 25 connected by longitudinal members 24, integral therewith, and on each sill are three columns integral therewith, two end columns 25, 26, and a center column 27, supporting transverse beams 28, integral with 30 the columns and connected by longitudinal joists 29 integral with the beams. These joists are sufficient in number for supporting a deck 30 preferably of concrete. This is 35 not only the floor of the wharf but also constitutes a wide horizontal girder which serves to stiffen the entire structure. Diagonal braces, as 31, Figs. 3 and 4, may be provided for additional stiffness, between the 40 tops of the end columns 25, 26, and the adjacent sills 23. In most cases bracing in alternate pairs of bays will be found sufficient, and the braces on the side next to the bank may be omitted in some instances, as in Fig. 2. Diagonal braces may also be provided 45 between the columns 26 and 27, as 31^a, 31^a, Fig. 3, in each or some of the transverse bents comprising the sills 23, columns 26, 27, and transverse beams or cross-bearers 28. It will be understood that the braces 50 are preferably integral with the parts which they adjoin.

Mooring bitts 32 are shown on the pier, Fig. 1. A row of wooden fender piles, one 55 of which is shown at 33, Fig. 2, may be set along the outer side of the pier at suitable intervals, and may be connected by upper and lower timber string pieces 34.

The concrete superstructure of the stiffeners shown at 14, 15, Fig. 1, may be of simpler 60 character than that of the main portion of the wharf. As illustrated in Figs. 6, 7 and 8 it comprises transverse sills 35, arranged on the supporting piles 20, 21, 22, and integral therewith. These sills are connected at the 65 center by longitudinal members 36 and on

their ends are columns 37 supporting transverse beams 38 which in turn support joists 39 over which the deck 30 is extended. It will be understood that the parts mentioned are composed of reinforced concrete and are 70 integral with each other, as in the case of the main portion of the pier.

From the foregoing it will be seen that the structure is practically monolithic, thus utilizing in an efficient manner the strength 75 of the individual units and enabling the structure to resist as a whole any stresses exerted on a particular portion. The large number of piles forming the substructure afford maximum resistance to vertical and 80 lateral displacement in the relatively soft bed of the river, and since the piles are all rigidly connected by a superstructure which is itself rigid, horizontal forces acting against a point on the superstructure and 85 tending to break the immediately adjacent piles are resisted not only by the latter but also by distant piles on either side. Reference to the drawing, especially Figs. 2, 4, 6 and 8, will reveal the open character of the 90 construction. This feature, which is due in part to the arrangement of the piles in bays, is of special advantage. In a stream such as the Mississippi, which carries enormous quantities of soil and other products 95 of erosion, any obstruction to the current, causing loss of velocity, permits deposition of silt in great amount, which not only results in shoaling the stream but also causes severe lateral stresses on the piling from the 100 up-stream side. This deposition is greatest during high water. For example, referring to Fig. 2, if the normal surface of the river bed (sloping upwardly toward the bank) is that indicated at *n-p*, silting during a 105 stage of high water may change the slope to that indicated by *n-r*. When the water recedes this accumulation slides back toward the center of the river, exerting stresses 110 which in many cases wooden piles have been found unable to withstand. In the construction illustrated the arrangement of the piles in bays, giving wide spaces entirely 115 free of obstruction, permits this outflow to proceed gradually and with minimum interference. The superstructure, which may be almost wholly submerged at high water is composed of heavier members but they are fewer in number than those of the sub-structure and hence do not offer materially 120 greater obstruction to the current at such times.

It is to be understood that the invention is not limited to the details herein specifically illustrated and described but can be embodied in other forms without departure 125 from its spirit as defined by the following claim.

I claim:—

In a wharf for use along, but spaced from, 130

a river bank, a monolithic structure consisting of a longitudinal framework substantially parallel to the bank, and stiffening members extending from said framework to the bank, said framework being supported by widely separated groups of piles, each group comprising a row of vertical piles closely spaced transversely of said framework and one or more inclined piles; said

stiffening members being supported by widely spaced groups of piles, each group comprising vertical piles and one or more piles inclined in a plane perpendicular to the bank, substantially as described. ¹⁰

In testimony whereof I hereto affix my ¹⁵ signature.

MAXWELL M. UPSON.
